UNITED STATES PATENT OFFICE.

JAMES FRANK, OF OLD FORGE, PENNSYLVANIA, ASSIGNOR, BY DIRECT AND MESNE ASSIGNMENTS, TO PITTSSTON HOME HELPS MANUFACTURING COMPANY, OF PITTSSTON, PENNSYLVANIA, A CORPORATION OF PENNSYLVANIA.

CLOTHESLINE SUPPORT.

Application filed February 29, 1928. Serial No. 258,114.

The present invention comprehends the provision of a support for pulley clothes lines, adapted to be mounted upon a window to permit the line to extend within the room, so that 5 hanging of the clothes can be accomplished in a quicker, easier and safer manner.

The invention contemplates the use of an adjustable pulley support mounted upon a suitable window bracket and capable of being 10 extended within the room or projected therefrom to permit closing of the sash, together with means for clamping and holding the line taut against the bracket, with the pulley support in its projected position.

15 An important object of the invention resides in the provision of a bracket mounted for horizontal pivotal adjustment so that the pulley support mounted thereon can be arranged at any desired angle as the occasion 20 may require, due to the location of the other end of the line, or the pitch of the latter.

In carrying out the invention, I provide a novel bracket construction for the above mentioned purpose, and which is also used as a 25 part of means employed for clamping and holding the line taut for use, that is to say, when use of the aforementioned pulley support has been dispensed with.

Another important object of the invention 30 resides in the provision of means whereby the clamping plate can be very quickly and conveniently locked against the bracket for use, or released to swing to its inactive position.

Other objects and advantages will appear 35 from the following detail description when read in connection with the accompanying drawings, and wherein like numerals of reference indicate similar parts in the several views.

40 Figure 1 is a vertical sectional view through a window construction, showing how the invention is mounted, and also illustrating how the line is clamped and held taut with the pulley support in its inactive projected position.

45 Figure 2 is a similar view showing the pulley support extended within the room for use, and the clamp released to permit the line to be moved over the pulley.

50 Figure 3 is a sectional view on line 3—3 of Figure 1.

Figure 4 is a sectional view on line 4—4 of Figure 1.

Figure 5 is a plan view of the bracket showing the pulley support at a right angle to the 55 window frame.

Figure 6 is a similar view showing how the pulley support can be arranged at any desired angle to the window frame.

Figure 7 is a view showing the component 60 parts of the bracket separated.

The device forming the subject matter of the present invention embodies what is termed a pulley support in the nature of an arm indicated at 10. This arm is slidably mounted upon a suitable window bracket, and terminates at one end to provide a hook 11 adapted to support the pulley 12 as illustrated. Consequently, the arm 10 can be extended within the room, subsequent to raising the sash, and when 70 so positioned the line 13 held sufficiently taut, but allowed to be moved about the pulley. By reason of the arrangement it is obvious that the person using the line can hang the clothes thereon or remove the clothes therefrom while standing within the room, that is to say without the necessity of leaning, stretching or reaching out of the window for this purpose, as is now customary. Therefore, the invention provides a means whereby 80 the hanging of clothes can be accomplished not only in a safer, but a more expeditious manner. After the clothes are hung upon the line, the arm 10 is wholly projected out of the window, so that the sash can be properly 85 closed, this position of the parts being clearly illustrated in Figure 1. However, before the arm 10 is so projected, the clothes line is clamped and held taut for use in a manner to be hereinafter more fully described. The de-

vice, of course, is susceptible for use with any and all kinds of pulley lines, but due to the location of the outer extremity of the line, or the pitch of the latter, it is frequently necessary to shift the arm 10 at some definite angle with 90 relation to the window frame to meet such conditions.

Therefore, I have devised a window bracket of novel construction and particularly advantageous for use in the foregoing connection. 100 In other words, the bracket not only supports the arm 10 for sliding movement, and permits

said arm to be arranged at any desired angle, but it is also employed as part of the means for holding the line taut, independently of the pulley support.

5 While the bracket as a whole may be varied for said purposes, it is preferably made in two sections as illustrated in Figure 7. The section 14 is constructed from a single blank of material and bent to provide upper and lower parallel ears 15 each having a central opening 16. The body portion of this particular section is slit along spaced transverse lines, and the separated portion is then bent rearwardly at a right angle to provide an attaching flange 17 by means of which the section is secured to the outer side of the window frame. The flange of course is provided with spaced openings 18 to accommodate suitable fastening elements. This section is fixed with relation 10 to the window frame, but the other section 19 is mounted thereon for horizontal swinging movement.

The section 19 is also formed from a single blank of material having its ends bent to provide spaced parallel ears 20. Each is provided with a central opening 21 adapted to register with the opening 16 of the adjacent ear 15, of the fixed section, when said sections are associated. Suitable fastening elements 22 are passed through said openings to support the section 19 for adjustment. The uppermost ear 20 of the section 19 is provided with spaced detents 23 to engage the adjacent ear of the section 14 and thus assist in frictionally maintaining the movable section 19 in any given adjusted position. Riveted or otherwise suitably secured to the movable section 19 is a channel-shaped guide member 24, the latter extending transversely across said section adjacent its upper end. Manifestly the pulley supporting arm 10 is slidably supported by the member 24 and held fixed with relation to the bracket in any given position by a thumb screw 25. Consequently when the arm 10 is extended within the room, the screw 25 is tightened to hold the arm immovable, and at the same time maintain the line 13 sufficiently taut.

However, as hereinabove stated, the bracket section 19 is also employed as part of the means for holding the line taut independently of the arm 10, or when the latter occupies its projected inactive position. With this object in view the body of the bracket section 19 is ribbed or corrugated as at 26 to cooperate with annular ribs or corrugations 27 formed on the clamping plate 28. This plate 28 is hinged at one end to the lower edge of the bracket section as at 29, so that it can be suspended therefrom when not in use as illustrated in Figures 2 and 3. The plate 28 can vary in size and contour without departing from the inventive idea, but it is preferably of a length to extend along the major portion 60 of the bracket section 19 when arranged parallel

in clamping relation therewith. The plate 28 is of course swung to its active position to clamp the line and hold it taut, before the arm 10 is released and shifted to its projected position as illustrated in Figure 1.

Any suitable means may be employed for holding the clamping plate 28 in its active position, but I preferably employ a lever 29 having a substantially square offset extremity 30 which is eccentrically pivoted between 70 companion lugs 31 carried by the section 19 of the window bracket. By reason of this construction the lever 29 remains, or is held by the offset extremity 30 by the resiliency of the section 19 in either its active or inactive position. The lever 29 is slightly curved, and preferably provided with a rib 32 which is adapted to be received by the adjacent corrugation of the plate 28 when the parts are arranged as shown in Figures 1 and 3. The free end of the plate 28 is notched as at 33 to permit the offset extremity 30 of the lever to operate with the plate 28 in its upright active position.

I desire to have it known that I do not limit myself to the details of construction herein illustrated and described, and that I reserve the right to make such changes as fall within the scope of the appended claims.

What is claimed is:

1. In a clothes line support, a window bracket including complementary substantially U-shaped sections having their parallel end portions overlapped, one of said sections having its body portion bent to provide a right angularly and longitudinally disposed attaching flange, the other of said sections being supported on the first mentioned section for horizontal pivotal movement, a channel-shaped guide arranged transversely of said movable section, an arm slidable through said guide, a pulley supported at one end of said arm and over which the line is trained, means for holding the arm fixed with relation to said section, a clamping plate hingedly mounted on the lower end of said section, and adapted to be arranged in parallelism therewith to hold the line therebetween taut independently of said arm, and means for holding said plate in said position.

2. In a clothes line support, a window bracket including complementary substantially U-shaped sections, the body portion of one section being bent to provide a right-angularly and longitudinally disposed attaching flange, the other section being supported on the first mentioned section for horizontal pivotal movement, an arm supported on the movable section and slidably transversely thereof, a pulley arranged at one end of the arm and over which the line is trained, means for holding the arm fixed in a given position with relation to said movable section, the body portion of the movable section having longitudinal ribs, a clamping plate hingedly 130

mounted on the lower end of said movable section and formed with spaced longitudinal ribs, to cooperate with the ribs on the bracket, when said plate is arranged parallel thereto with to hold the line taut independently of said arm, a lever including an offset extremity pivoted on the movable section and cooperating therewith to hold the lever in either an active or an inactive position, said lever being curved, and a rib formed on the lever to engage the plate when the lever is positioned to hold the plate in clamping relation with the bracket. 10

In testimony whereof I affix my signature.

JAMES FRANK.
